REFRIGERATING APPARATUS

Malcolm G. Shoemaker, Doylestown, Pa., assignor
to Philco Corporation, Philadelphia, Pa., a corporation of Pennsylvania

Application August 17, 1951, Serial No. 242,290

6 Claims. (Cl. 62—8)

1

The present invention relates to refrigerating apparatus and, more particularly, to a refrigeration system and valve means therefor which provides for heating of the evaporator to effect removal of frost which, during normal operation of the system, accumulates on the surface of the evaporator. More specifically, the invention has to do with improvements in the type of refrigeration system disclosed in my co-pending application, Serial No. 189,183, filed October 9, 1950, now Patent No. 2,631,441, issued March 17, 1953.

In accordance with the teachings of my above identified co-pending application, defrosting is accomplished through the agency of a valve structure disposed in the suction line and having connection with the discharge side of the compressor. This valve structure is adapted, through suitable passage means, to by-pass the main flow restrictor or capillary tube and, concurrently, to establish flow of refrigerant from said discharge side of the compressor, through the suction line and thence through the evaporator in a direction reverse with respect to the normal direction of flow through said evaporator. The system includes a continuously open return passage or connection which, under defrosting conditions, conducts liquid refrigerant flowing from what is normally the inlet side of said evaporator, directly back to the compressor.

It is an important object of the present invention to improve the construction and operation of the valve structure which is incorporated in a system of the above mentioned type to control the reversal of the flow of refrigerant through the evaporator. Broadly, this object of the invention is realized by providing an improved valve arrangement which is associated with the refrigeration system in a novel manner so as to operate directly in response to pressure conditions which are created in the system by initiation and termination of a defrosting cycle. A valve arrangement constructed and used in accordance with this invention, has the advantage of doing away with the need of employing specially and accurately designed mechanical pressure applying and compensating means, such as a spring, to govern the actuation of the valve in its flow controlling function. As a result, adequate operation of the valve is assured and is not jeopardized by possible failure of mechanical spring means.

The novel features of the invention and the manner in which the above are recited and other objects and advantages are best achieved, will clearly appear from the following description of the embodiment shown in the accompanying drawing, in which:

2

Figure 1 is a diagrammatic representation of a refrigeration system including defrosting apparatus embodying the present invention and showing the condition which exists in the system during a normal refrigerating cycle;

Figure 2 is a view similar to Figure 1, but shows the condition which exists in the system during a defrosting cycle; and

Figure 3 is an enlarged cross-sectional view of the pressure responsive valve constructed in accordance with the invention to control the flow of refrigerant in the system illustrated in Figures 1 and 2.

With more particular reference to the drawing, 15 the embodiment as illustrated in Figures 1 and 2, comprises the usual elements of a refrigeration system of conventional type, namely, a motor-compressor 10, a condenser 11, and an evaporator 12. These elements are connected in series 20 flow circuit through the agency of suitable connections and conduits, including flow restrictor or capillary tube 13 and suction line 14. As is customary, the evaporator is disposed in heat 25 exchange relation with a compartment or zone to be cooled, said compartment or zone being diagrammatically shown by broken line C. Also, as is customary, the capillary tube and the suction line may, if desired, be associated in heat exchange relation. This association has been omitted from the drawing in the interest of simplicity and clarity of illustration.

In addition to the above mentioned usual components, the system according to the invention, 35 includes a solenoid valve device 15 and a pressure responsive valve device 16. Also, in accordance with the invention, the system includes a connecting conduit 17 and a continuously open by-pass conduit 18. The connecting conduit 17 has one end connected with the solenoid valve device and the other end connected with the pressure responsive valve device. The continuously 40 open by-pass conduit 18 has one end connected with the inlet of the evaporator at its juncture with the outlet of the flow restrictor or capillary tube, and the other end connected with the suction line at a point between the motor-compressor and the pressure responsive valve device.

The solenoid valve device comprises a body 19 providing two chambers 20 and 21 which are adapted to communicate with each other through the opening 22 (see Figure 2) in a valve seat structure 23 which separates said chambers. Communication between said chambers is normally prevented (see Figure 1) by means of a valve element 24 in engagement with said seat 23. The valve body 19 is provided with three ports

25, 26 and 27. Ports 25 and 26 open into one chamber 20 of the valve body; one port 25 being connected with the outlet of the condenser, the other port 26 being connected with the inlet of the capillary tube. The remaining or third port 27 opens into the other chamber 21 and is connected with the aforementioned connecting conduit 17 which leads to the pressure responsive valve device 16.

The pressure responsive valve device comprises an elongated body 28 which, as clearly seen in Figure 3, has a longitudinal bore 29 extending therethrough. One end of the valve body is provided with an enlarged portion 30 which is generally cup-shaped and is closed by means of a cap 31. This cup-shaped portion and its cap cooperate to form a hermetically sealed housing enclosing a diaphragm 32 which stretches across said housing, the marginal edge portion 33 of said diaphragm being fixedly retained between flat clamping surfaces 34 and 35 provided on said cup-shaped portion and cap, respectively. A valve stem 37 having one end rigidly affixed, as at 38, to the center of the diaphragm, depends from the latter and extends into the bore 29 in the valve body. The valve stem is provided with a passageway 39 which, as shown at 40, is in open communication with space 41 defined by the valve cap and the diaphragm and which, as shown at 42, is also in open communication with a chamber 43. This chamber is conveniently formed by enlargement of a portion of said bore 29 and is in open communication with space 44 defined by the cup-shaped portion and the diaphragm. For the purpose of establishing open communication between said chamber 43 and said space 44, the aforementioned bore 29 is of greater cross-sectional dimension than the cross-sectional dimension of the valve stem. The chamber 43 also communicates, as at 45, with another chamber 46 which is provided by a still greater enlargement of the internal bore in the valve body 28. The communication between chambers 43 and 46 is controlled by means of a valve element 47 which is provided on the valve stem 37 and which is adapted for engagement with a valve seat 48 between said chambers. The valve body is provided with three ports 49, 50 and 51; port 49 opens into chamber 43 and is connected with the suction line 14 extending from the evaporator; port 50 opens into chamber 46 and is connected with the suction line portion indicated at 14a which leads to the motor-compressor; and port 51 opens into space 44 and is connected with the conduit 17 which, as hereinbefore indicated, is connected with the valve controlled chamber 21 in the solenoid valve body.

Referring again to Figures 1 and 3, it will be seen that the system is conventional insofar as the normal refrigerating cycle is concerned. During such normal refrigerating cycle, the solenoid valve element 24, as seen in Figure 1, engages its valve seat 23, and the pressure valve element 47, as seen in full lines in Figure 3, is moved away from its seat 48. Under these conditions, hot gaseous refrigerant is delivered from the compressor to the condenser where the compressed gaseous refrigerant gives up heat to the ambient air and is converted to liquid state. From the condenser, liquefied refrigerant passes into chamber 20 of the solenoid valve body 19 and thence flows through the capillary tube 13 and the evaporator 12 where the refrigerant vaporizes and, in the process, absorbs heat from air within the compartment or zone C. Heat-laden vaporized

refrigerant which flows from the evaporator through suction line 14, passes through intercommunicating chambers 43 and 46 in the pressure valve body 28 and then flows through the suction line portion 14a into the compressor. During the above described refrigeration cycle, no flow of refrigerant occurs through conduit 17 since this conduit is sealed-off by the solenoid valve element 24, and the flow through the pressure valve takes place through suction line section 14, intercommunicating chambers 43 and 46, and suction line section 14a. Under these conditions, it will be understood that the pressure in chamber 43 determines the pressures which exist on opposite sides of the diaphragm since said chamber is in open communication with cavities or spaces 41 and 44 through bore 29 and passageway 39, respectively. Thus the pressures which prevail in said chambers and in said cavities are substantially the same so that the diaphragm is maintained in neutral position and the valve element 47 tends to remain in open position as long as the normal refrigerating cycle is in progress, that is to say, as long as the condition represented in Figure 1 exists. It is pointed out that during this refrigerating cycle or condition, the continuously open by-pass connection 18 performs a useful function in that flash gas from the capillary tube is returned to the compressor, rather than passing through the evaporator where such flash gas tends to reduce the effectiveness of the evaporator. As shown in the illustrated embodiment, separation of the flash gas is conveniently accomplished by means of a separator device 52 interposed at the outlet of the capillary tube, the inlet of the evaporator and the inlet of said by-pass conduit 18. It is significant to note that the conduit or connection 18 is made as a restrictor. In practice, the restriction of this conduit or connection is just sufficient to prevent liquid refrigerant passing out of the capillary tube from flowing backwardly through said conduit or connection, and to insure that such liquid refrigerant will flow through the evaporator as is required during normal refrigerating operation of the system.

When it becomes desirable or necessary to defrost the evaporator, the refrigerating cycle is terminated and a defrosting cycle is initiated by mere actuation of the solenoid valve device to open the communication between chambers 20 and 21 in the body 19 of said valve device. In the embodiment shown, actuation of the solenoid valve is accomplished through the agency of a solenoid coil 53 which operates to cause movement of the valve element 24 away from its seat. Operation of this solenoid coil can be obtained through suitable control mechanisms. Such mechanisms are generally known in the art and since the present invention is not concerned with them, illustration and description of their construction and operation is not required herein.

The condition which exists in the system during a defrosting cycle, is best understood by referring to Figures 2 and 3. The high pressure refrigerant emerging from the condenser into chamber 20 in the solenoid valve body 19, passes into chamber 21 and out through conduit 17 into space 44 in the pressure valve body 28. The admittance of high pressure refrigerant into the space 44 results in displacing the diaphragm 32, as is represented in broken lines in Figure 3. This displacement of the diaphragm causes movement of the valve stem 37 which brings the valve element 47 in engagement with its seat 48, there-

by sealing communication between chambers 43 and 46 in the pressure valve body. From the space 44, the refrigerant passes through the bore 29 about the valve stem into chamber 43 and, thence, enters the evaporator through line 14. In circulating through the evaporator, the gaseous refrigerant condenses thus providing the necessary heat for melting the frost accumulated on said surfaces. From the evaporator, the refrigerant returns through conduit 16 and suction line section 14a to the compressor. It will be understood that in order to prevent mechanical difficulties due to liquid directly entering the compressor pump, the system utilizes the well known type of compressor in which the space within the shell or dome of the compressor is included in the low pressure side of the system. By using this type of compressor, the refrigerant which is in liquid state, due to the condensation occurring within the evaporator during defrosting, is reconverted to gaseous state by heat exchange taking place within the low pressure shell before entering the compressor pump. It is of importance to note that the restricted bore 29 impedes the flow of refrigerant which passes from cavity 44 to chamber 43 so that, during the defrost cycle, the pressure in said cavity is always higher than the pressure in said chamber. Likewise, during the defrost cycle, the pressure in cavity 44 is always higher than the pressure in cavity 41 since the latter cavity is in open communication, through passageway 39, with chamber 43 in which a reduced pressure prevails for the above stated reason. The result, of course, is that the opposite sides of the diaphragm 32 are subjected to the required pressure differential to insure maintenance of the valve in closed position, as is illustrated in broken lines in Figure 3, so long as the condition represented in Figure 2 exists.

When the defrost cycle is completed, the solenoid coil 53 is de-energized, for instance, by means of suitable known control (not shown), to move the valve element 24 in engagement with its seat. Seating of this valve element seals off the communication between chambers 26 and 21 and interrupts the flow of high pressure refrigerant through conduit 17, whereupon the pressures on the opposite sides of the diaphragm equalize since sealing-off of said conduit cuts out the source of high pressure to cavity 44. The diaphragm then is free to return to its normal position and to release the valve element 47 for movement to open position under influence of the pressure difference between chamber 43 and chamber 46. With opening of said valve element the pressures throughout the valve, that is the pressures in chambers 43 and 46 and in cavities 41 and 44, equalize and the normal refrigeration cycle is restored.

From the foregoing description, it will be appreciated that the present invention provides a defrosting system which is characterized by unusual constructional simplicity and operational reliability. Particularly, it will be appreciated that the peculiar construction of the pressure valve and its novel association in the system are significant features of the invention, and that these features make it possible effectively to control the refrigerating and the defrosting operations without having to depend on intricate mechanical means for such operations.

I claim:

1. Means operable to control the flow of refrigerant through the evaporator of a refrigeration system of the type having a compressor, condenser and a restrictor in series flow circuit with the evaporator, comprising a valve body having two intercommunicating chambers one of which is

- 3 adapted for connection with the outlet of the evaporator and the other of which is adapted for connection with the inlet of the compressor, a pressure operated diaphragm enclosed in said valve body, a valve member carried by said diaphragm and operable to establish and to prevent communication between said chambers, passage means establishing communication between one side of said diaphragm and that one chamber which is adapted for connection with the outlet 10 of the evaporator, other passage means establishing communication between the other side of the diaphragm and said one chamber, and selectively controllable conduit means communicating with said one chamber and adapted for connection 15 with the condenser to establish communication between the latter and said one chamber.
2. Control means as set forth in claim 1, in which the first mentioned passage means is constructed as a restrictor.
- 25 3. In combination with a refrigeration system of the type having a compressor, a condenser, a restrictor and an evaporator; means operable to control the flow of refrigerant through the evaporator comprising a valve body having a first chamber connected with the outlet of the evaporator and a second chamber connected with the inlet of the compressor, a pressure operated diaphragm enclosed in said valve body and cooperating with portions thereof to define a first cavity to one side of said diaphragm and a second cavity to the other side of said diaphragm, a valve member connected with said diaphragm and normally positioned to establish communication between said chambers, first means establishing open communication between said first cavity and said first chamber, second means establishing open communication between said second cavity and said first chamber, and selectively controllable means operable to connect said first cavity with the condenser to provide for admission of refrigerant at high pressure in said cavity to cause movement of said diaphragm and valve to a position preventing communication between said chambers, said first means being so constructed as to impede the flow of refrigerant from said first cavity to said first chamber to provide for reduced pressure in said chamber when the latter is connected with the condenser.
- 40 4. In combination with a refrigeration system of the type having a compressor, a condenser, a restrictor and an evaporator; means operable to control the flow of refrigerant through the evaporator comprising a valve body provided with two intercommunicating chambers, one communicating with the outlet of the evaporator and the other communicating with the inlet of the compressor, a diaphragm enclosed in said body and cooperating with portions thereof to define a cavity to one side of the diaphragm and a cavity 45 to the other side of the diaphragm, selectively controllable communication means between one of said cavities and the condenser, a valve stem attached to said diaphragm and provided with a passageway establishing communication between the other of said cavities and the said one chamber which communicates with the outlet of the evaporator, a valve seat between said chambers, and a valve element carried by said stem and operable in cooperation with said seat to establish and to prevent communication between
- 50 55 60 65 70 75

said chambers through movement of the stem by actuation of the diaphragm in response to pressure conditions created on opposite sides of the diaphragm by operation of said selectively controllable communication means.

5. In combination with a refrigeration system of the type having a compressor, a condenser, a restrictor, an evaporator; means operable to control the flow of refrigerant through the evaporator comprising a valve body provided with two intercommunicating chambers, one communicating with the outlet of the evaporator and the other communicating with the inlet of the compressor, a diaphragm enclosed in said body and cooperating with portions thereof to define a cavity to one side of the diaphragm and a cavity to the other side of the diaphragm, selectively controllable communication means between one of said cavities and the condenser, a valve stem attached to said diaphragm and provided with a passageway establishing communication between the other of said cavities and the said one chamber which communicates with the outlet of the evaporator, a valve seat between said chambers, a valve element carried by said stem and operable in cooperation with said seat to establish and to prevent communication between said chambers through movement of the stem by actuation of the diaphragm in response to pressure conditions created on opposite sides of the diaphragm by operation of said selectively controllable communication means, and a continuously open passage operable, when said valve element is moved to prevent communication between said chambers, substantially to by-pass the restrictor and to deliver refrigerant flowing from the evaporator back to the inlet side of the compressor.

6. In a refrigeration system of the type having elements including a compressor, a condenser, a restrictor, an evaporator, and conduit means including suction and feed lines connecting said elements in series flow circuit, means operable to interrupt normal flow of refrigerant from the evaporator through the suction line to the compressor and to establish modified flow of refrigerant from the discharge side of the compressor through said suction line and to the evaporator, said means comprising a valve body interposed between sections of the suction line and provided with two chambers one of which is connected with the suction line section leading from the evaporator and the other of which is connected with the suction line section leading to the compressor, a pressure operated diaphragm enclosed in said valve body, a valve member carried by said diaphragm and operable to establish and to prevent communication between said chambers, means in said valve body establishing communication between said one chamber and one side of said diaphragm, means in said valve member establishing communication between said other chamber and the other side of said diaphragm, and a continuously open passage operable, when said modified flow is established, substantially to by-pass the restrictor and to deliver refrigerant flowing from the evaporator back to the inlet side of the compressor.
